AUGUSTUS R. HOBBS, OF ELIZABETH, NEW JERSEY.

Letters Patent No. 78,965, dated June 16, 1868.

IMPROVED FANNING-ATTACHMENT FOR ROCKING-CHAIRS.

The Schedule referred to in these Letters Patent and making part of the same.

TO ALL WHOM IT MAY CONCERN:

Be it known that I, AUGUSTUS R. HOBBS, of Elizabeth, in the county of Union, and State of New Jersey, have invented a new and improved Fanning-Attachment to Rocking-Chairs; and I do hereby declare that the following is a full, clear, and exact description thereof, which will enable others skilled in the art to make and use the same, reference being had to the accompanying drawings forming part of this specification.

This invention relates to a new and improved attachment to rocking-chairs, whereby a rotating motion is communicated by the rocking of the chair to fans so situated as to cool and refresh the occupant of the same.

It consists in the construction, combination, and arrangement of the parts as hereinafter more fully set forth. In the accompanying plate of drawings—

Figure 1 is a side view of my invention, a portion of the casing or tube being removed to show the construction.

Figure 2 is a detail sectional view of the fan-shaft and pinion, together with the clamp, by means of which the same is held upon the tube.

Similar letters of reference indicate corresponding parts, taken in the line $z z$, fig. 1.

Within the bore of any metallic tube, A, is fitted a metallic rod, B; said rod B being provided with grooves upon the upper end of the same; for about one-third of the length of the rod B, so as to form a cylindrical rack, as shown, said rod being of sufficient length to extend from the floor to about fifteen inches above the arm of the rocking-chair to which the same is to be attached.

The tube A must be of sufficient length to permit of a reciprocating movement of the rod B within the same, and may be of any convenient diameter, or of such diameter as to be of about one-half or five-eighths of one inch in the bore, and may be closed at the top, and finished or ornamented according to the taste.

Within a bent metallic clasp, C, and rotating in bearings in the two parts of the same, as shown in the drawing, is a metallic shaft, D. Keyed upon the shaft D, in the ordinary way, is a spur-gear'd pinion, E, having teeth so formed as to fit into the grooves in the rod B, through the two parts of the clasp C, near one end of the same, and working in a screw-thread in one part thereof is a set-screw, F.

The clasp C is so formed as to receive the tube A between the two parts thereof, as shown in the drawing, the object of the screw F being to bind the two parts of the clasp C firmly upon said tube A, and so that the tube A will support the shaft D, and the fans upon the same. The clamp C may be supported by suitable braces attached to the tube A, or in any other convenient manner.

Through the tube A is cut a slot to receive the teeth of the pinion E, as shown. Around the rod B, the lower end resting upon a collar, H, as shown, is a coiled spiral spring, I, attached by the upper end to the tube A, as shown, so that when the rod B is forced up into the tube A, the shaft D will be rotated in one direction by rack upon the rod B working in the teeth of the pinion E, and will be rotated in the opposite direction when left free, by the force of the spring I. The bottom end of the rod B rests upon the floor, and is furnished with a wheel, J, serving as a pivot on which the rod A vibrates in the motion of the chair. The tube A may be made in two parts, jointed by a collar K, by means of which the upper part of the tube A may be turned upon the lower part of the same, by means of which the fans G may be adjusted. The fans G may be any of the palm-leaf or other fans now commonly in use.

Upon the shaft D, at any convenient point, is a collar, L, said collar L being furnished with three or more arms, to each of which a fan, G, may be attached, said collar L being held upon the shaft D by a set-screw, as shown.

The whole may be secured to the arm and rocker of any rocking-chair, M, as shown in the drawing, or in any convenient position or method.

I claim as new, and desire to secure by Letters Patent—

1. The grooved rod B, in combination with the shaft D and any fans G, substantially as shown and described, and for the purposes set forth.

2. The tube A and grooved rod B, or its equivalent, and spring I, by means of which a reciprocating

rectilinear motion of the rod B is changed to a reciprocating rotary motion of the shaft D, and any fans; G, in combination with any rocking-chair, M, substantially as shown and described.

3. The device for holding the shaft D in proper position with respect to the rod B, substantially as shown and described.

4. The collar K, in combination with the tube A, made in two parts, for adjusting the position of the fans, G, substantially as shown and described.

5. A fanning-attachment to rocking-chairs, substantially as shown and described.

The above specification of my invention signed by me, this 27th day of December, 1867.

AUGUSTUS R. HOBBS.
